Primary Examiner — Ricky Pham*(74) Attorney, Agent, or Firm* — Notaro, Michalos & Zaccaria P.C.(57) **CLAIM**

The ornamental design for a pizza maker, as shown and described.

DESCRIPTION

FIG. 1 is a front right perspective view of a pizza maker showing my design;

FIG. 2 is a left view thereof;

FIG. 3 is a right view thereof;

FIG. 4 is a front view thereof;

FIG. 5 is a rear view thereof;

FIG. 6 is a top view thereof; and,

FIG. 7 is a bottom view thereof.

The broken lines represent portions of the pizza maker that form no part of the claimed design.
